UNITED STATES PATENT OFFICE.

WILL W. JOHNSON AND PAUL P. RICKENBACHER, OF WASHINGTON, D. C.

BRAKE-BLOCK.

SPECIFICATION forming part of Letters Patent No. 361,422, dated April 19, 1887.

Application filed February 28, 1887. Serial No. 229,187. (No model.)

To all whom it may concern:

Be it known that we, WILL W. JOHNSON and PAUL P. RICKENBACHER, citizens of the United States, residing at Washington city, 5 in the District of Columbia, have invented certain new and useful Improvements in Brake-Blocks, of which the following is a full, clear, and exact description, reference being had to the accompanying drawings, forming a part of 10 this specification, in which—

Figure 1 represents a perspective view of a brake-block embodying our invention. Fig. 2 is a longitudinal sectional view of the same. Fig. 3 is a cross-sectional view on the line $x-x$ 15 of Fig. 2.

Our invention relates to certain improvements in brake-blocks for vehicles; and it consists in the peculiar constructions and combinations of devices which we will hereinafter 20 fully describe and specifically claim.

To enable others skilled in the art to which our invention appertains to make and use the same, we will now describe its construction and indicate the manner in which the same is carried out.

In the said drawings, A represents a brake bar or shaft such as is usually located in the front of the vehicle's rear wheels, and B represents a brake-block secured to said shaft 30 and adapted to be brought into contact with the periphery of said wheel in the usual manner.

The shaft A in the present case has a threaded end, a, which is engaged by a nut, b, and is 35 also provided with a shoulder or flange, c, the lower surface of which is rounded or cam-shaped, for a purpose we will hereinafter specify.

The brake-blocks of many vehicles now in 40 use have been constructed of wood, and sometimes the wearing-faces of these blocks are protected by a plate of metal or shoe; but in either case the wear upon the blocks, when applied to heavy road-wagons, was such that

45 in a comparatively short time the said blocks were worn to such an extent as to greatly impair their usefulness, thus rendering it necessary to replace them with new ones. In the present instance we have constructed our 50 block preferably of cast-iron, the slightly increased cost and weight of which is more than

compensated for by the length of time the block may be used. At the same time, owing to its shape, our block may be cast with but little trouble.

The said block B has its working face curved to correspond with the curvature of the wheel, and is provided on its rear with a perforated lug or extension, d, the inner face of which is set back sufficiently far from the corresponding face of the block as to form a shoulder or seat, e, as shown in Figs. 1 and 2, and against which the curved or cam-shaped portion of the flange c rests. The outer end of the shaft A is passed through the perforation g in the 65 lug or extension d until the flange e is brought against the inner face of said lug, and the nut b screwed upon the threaded end of said shaft until it meets or abuts against the outer face of the lug, but not with sufficient force to prevent the brake-block from turning slightly 70 upon its axis.

From this description it is manifest that when the brake-block is brought against the tire of the wheel it will rotate upon the shaft, and thus bring its working face squarely against said wheel. By reason of the curved or cam-shaped flange the block is permitted to rotate, but only sufficiently to cause it to be brought directly against the tire of the contiguous 80 wheel.

One of the most common and annoying results incident to many of the blocks as at present constructed is the liability of the same turning on its axis sufficiently to throw the 85 block entirely over, thus impairing the working of the block and necessitating its removal and readjustment. This objectionable feature is overcome by the use of our block, inasmuch as the block, by reason of its engagement with the cam-flange, cannot possibly under any circumstances rotate in an arc greater than what is necessary to bring the curved face of the block squarely against the periphery of the wheel.

The upper portion of that part of the shaft A within the lug or projection d is slightly cut away, as shown at h, to be engaged by a set-screw, l, whereby the shaft cannot be withdrawn from said lug without first loosening 100 the screw l, even though the nut b should by any accident become detached from the end of

the shaft. We are thus enabled to construct a cheap, substantial, and effective brake-block, and one which can under all circumstances be brought squarely against the wheel, even though a larger portion of its working face should be worn away.

Having thus described our invention, what we claim, and desire to secure by Letters Patent, is—

10. 1. The combination, with a brake-block having a shoulder, *e*, of a shaft or brake bar having a flange, *c*, provided with a cam-surface engaging said shoulder and limiting the rotary movement of said block, substantially as herein described.
15. 2. The combination, with the metallic block *B*, having the perforated lug or extension *d* and a shoulder, *e*, of a shaft or brake-bar en-

gaging said lug, and having a flange, *c*, the lower surface of which is rounded or cam-shaped, said flange engaging said shoulder and limiting the movement of the block, substantially as herein described.

3. An improved brake-block comprising the metallic block *B*, the shaft *A* engaging said block, and having the flange *c* seated against a shoulder thereon, said flange being provided with a cam-surface, as described, and a set-screw engaging and holding the shaft, substantially as herein described.

WILL W. JOHNSON.
PAUL P. RICKENBACHER.
